UNITED STATES PATENT OFFICE.

GILDEROY O. BURLEW, OF NEWARK, NEW JERSEY.

DENTAL ABRASIVE OR GRINDING DISK.

1,355,888.

Specification of Letters Patent. Patented Oct. 19, 1920.

Application filed September 6, 1919. Serial No. 322,176.

To all whom it may concern:

Be it known that I, GILDEROY O. BURLEW, a citizen of the United States, residing in the city of Newark, in the county of Essex 5 and State of New Jersey, have invented certain new and useful Improvements in Dental Abrasive or Grinding Disks, of which the following is a full, clear, and exact description, such as will enable others skilled in 10 the art to which it pertains to make and use the same, reference being had to the accompanying drawings, and to numerals of reference marked thereon, forming a part of this specification.

15 It is customary in dental work to employ wheels or disks fixed upon a revolving mandrel for the purpose of grinding, cutting, and polishing teeth. These grinding wheels or disks are mounted upon a steel mandrel 20 and when so mounted the grinding wheel or disk becomes a rigid and unyielding body which causes great discomfort and pain in preparing abutments for crowns and bridge work.

25 Furthermore, the periphery of the grinding wheels or disks so mounted have a tendency to become irregular thereby causing great shock and impairing the efficiency of the work.

30 A grinding disk or wheel so mounted will run at an exact right angle to the revolving mandrel upon which it is fixed.

The grinding disk is preferably made of a compound consisting of fine particles of 35 carborundum or other suitable abrasive grit material together with an integrating medium of primary plastic or mixable nature and capable of hardening in homogeneous mass to the desired degree, as vulcanizable 40 rubber or a suitable substance that will securely hold the abrasive particles, but will itself wear away as the particles wear away in the use of the disk. The disk, is primarily molded into shape from the com-

45 pound while in a plastic or unsolidified condition. The composition of the disk is then solidified by vulcanization or well-known treatment for hardening materials of this nature. The disk is preferably 50 formed with an integral boss or hub projecting from one side thereof, said hub being provided with an aperture which receives the mandrel on which the disk is mounted for use.

55 The object of my invention consists in providing a disk of the character above de-

scribed with an elastic or yielding central core preferably of rubber, although cork felt or any other resilient substance may be substituted which has the same resiliency 60 and shock absorbing qualities as rubber, so that when fixed upon a revolving mandrel for the purpose of grinding, cutting or polishing teeth will not always run at an exact right angle to said mandrel, but owing 65 to the resilient central core will operate at an obtuse or acute angle to the mandrel.

The application of a resilient central core imparts to the periphery of the grinding disk or wheels, a certain amount of resiliency, thereby absorbing and taking away 70 the shock from the tooth.

These objects I perform in the preferred embodiment of my invention, which I have illustrated in the accompanying drawings, 75 to which reference is had, and in which similar characters of reference indicate corresponding parts in the several views.

In the drawings,—

Figure 1 represents, a plan view of my improved device.

Fig. 2 represents a sectional view taken on line $x-x$ of Fig. 1.

Fig. 3 represents, a plan view and side elevation of the soft rubber core.

Fig. 4 represents, a plan view of that portion of the carborundum disk which subsequently together with the soft rubber core, after being molded around and vulcanized together with said soft rubber core, forms 90 the completed disk; and

Fig. 5 represents, a modified form of disk in which the soft rubber center is flush with the faces of the disk.

In describing the product forming my invention, I will simultaneously describe the process of the same, so that those skilled in the art to which it pertains, may gain a full knowledge of the process, as well as the product.

100 In the drawings, 1 represents, a disk suitable for abrading, cutting, polishing, etc., according to the work to be done.

The disk 1 is preferably formed with an integral boss or hub 2 projecting from one side thereof, said hub being provided with an aperture 3 by means of which it is secured upon the mandrel.

105 In the process of making these disks I employ the central soft rubber hub 3 illustrated in Fig. 3 of the drawings, which is first placed into a suitable mold and I then 110

surround said hub 3 with the material which subsequently forms the disk and which consists preferably, of a compound consisting of fine particles of carborundum or other suitable abrasive grit material together with an integrating medium of primary plastic or mixable nature and capable of hardening in homogeneous mass to the desired degree, as vulcanizable rubber or a suitable substance that will securely hold the abrasive particles, so that the completed disk will consist of a portion approximating the shape illustrated in Fig. 4 of the drawings which is vulcanized hard, and the central part 15 namely the hub 3 will be given a soft vulcanization; there being no clear line of demarcation between such hard and soft parts, thereby producing a disk with an elastic or yielding center core so that when fixed upon 20 a revolving mandrel for the purpose of grinding, cutting, etc., it will not always run at an exact right angle to said mandrel, but owing to the resilient central core will operate at an obtuse or an acute angle to the mandrel, thus imparting to the periphery of the disk, a certain amount of resiliency, thereby absorbing and taking away the 25 shock from the tooth.

Experience has demonstrated that the de-

vice above described is a highly efficient one, 30 and while the device shown is the preferred embodiment of my invention, I do not care to restrict myself to the exact details of construction described, it being obvious that minor variations thereof not involving the 35 exercise of invention, may be made by any skilled mechanic, and such departures from what is herein described and claimed not involving invention, I consider as within the scope and terms of my claim. 40

I claim—

The process of forming abrasive or grinding disks, consisting in molding around an elastic or yielding center core of rubber adapted for soft vulcanization, a body of 45 abrasive grit together with an integrating medium of primary plastic or mixable nature such as rubber adapted for hard vulcanization and capable of hardening in homogeneous mass, giving the central core 50 a soft vulcanization and giving the body of the disk a hard vulcanization.

This specification signed and witnessed this 29th day of August 1919.

GILDEROY O. BURLEW.
